Des. 220,811
Patented May 25, 1971

220,811

TELEPHONE COUPLER

Charles Jerabek, Bay Shore, N.Y., assignor to
Vernitron Corporation, New York, N.Y.

Filed July 8, 1969, Ser. No. 18,583

Term of patent 14 years

Int. Cl. D14—03

U.S. Cl. D26—14

Fig. 3

Fig. 2

Fig. 4

Fig. 8

Fig. 5

Fig. 6

Fig. 7

FIG. 1 is an exploded perspective view of a telephone coupler showing my new design;

FIG. 2 is a top plan view thereof;

FIG. 3 is a right side elevation thereof;

FIG. 4 is a front elevation in a fully assembled condition;

FIG. 5 is a rear elevation with the cover member in an open position;

FIG. 6 is a left side elevation;

FIG. 7 is a bottom plan view; and

FIG. 8 is a front elevation.

I claim:

The ornamental design for a telephone coupler, substantially as shown and described.
